APPARATUS FOR CLASSIFYING MATERIAL

Joseph E. Kennedy, New York, N. Y., assignor to
Kennedy-Van Saun Mfg. & Eng. Corporation,
New York, N. Y., a corporation of Delaware

Application October 31, 1936, Serial No. 108,509

5 Claims. (Cl. 209—160)

This invention relates to the separating and classifying of material, such as ore or sand, by the wet method, wherein a mass of material is subjected to the action of a stream or streams of liquid, such as water, to separate and flow off from the mass particles of material of predetermined specified gravity or degree of fineness, and it is the principal object of the invention to provide improved means to subject the material to be separated and classified and consisting of solids of different degrees of fineness or specific gravity to the action of a stream or streams of liquid as the material is delivered into the container and the material collected in the container to effect a separation of particles of material below a predetermined specific gravity or of a predetermined degree of fineness from the mass of the material, and while it is adapted particularly for the separating of particles of material below a predetermined specific gravity from a mass of material, such as crushed ore, it is also adapted for the separating of foreign substances from a product, such as the separating of loam and colloidal matter from sand, and classify sand by separating of sand of predetermined degree of fineness from a mass of sand.

It is another object of the invention to provide means for this purpose which is adjustable to separate particles of different specific gravity and different degrees of fineness from a product, such as crushed ore or sand.

Another object of the invention is to provide apparatus of this character wherein there is effected a dewatering or reduction of the moisture content of the solids of the treated material and thus adapt the treated material to be transported by a belt conveyer.

It is a further object of the invention to provide in apparatus of this character means embodying a container into which the material to be treated is delivered and subjected to the action of a liquid as it is delivered into the container to effect classification of the material and adapted to collect classified material in the container and effect reduction in the moisture content of the collected material, and means automatically operative and controlled by the quantity of material collected in the container to discharge the material from the container.

A further object of the invention is to provide means to reduce material, such as ore, and in combination therewith provide means to which the reduced material is delivered from the reducing means to effect classification of the reduced material by the separation therefrom of material

within a predetermined degree of fineness or specific gravity and the returning of the coarse material to the reducing means for further treatment.

In carrying out the invention there is provided a container in the form of a tubular body, preferably of conical or hopper form, open at the opposite ends and yieldingly supported to have upward and downward vertical movement, said body being normally urged upward with no material therein and adapted to be moved downward proportional with the quantity of material therein, the material to be classified being delivered into the top of said body. The opening through the lower end of the body is provided with a closure supported to have movement toward and away from said end of the body and connected with the body to transmit closing movement to the closure by the upward movement of the body and opening movement to the closure by the downward movement of the body. Means are provided to deliver the material to the body to be classified and effect a spreading and directing of the material in opposite directions toward the side of the body as it is filled therein. To effect a separation and classifying of the material filled into the body nozzles adapted for connection with a source of liquid, such as water, are mounted in the wall of and open to the interior of the body, the nozzles being arranged in rows spaced longitudinally of the body within the top and bottom thereof and the nozzles disposed to direct the streams therefrom in an upward diverging direction and tangential to the inner side wall of the body, said liquid being adapted to be flowed off from the top of the body and flow off therewith separated material within a predetermined degree of fineness of specific gravity, and means, such as a launder, is provided to receive the liquid flowing from the top of the body, said launder being arranged to direct the liquid therefrom away from the body. In the use of the device in the classifying of crushed ore the classifier is used in conjunction with suitable material reducing means, and means are provided to deliver the reduced ore as it is crushed to the body of the classifier and to receive the coarse material settled in and discharged from the body and transport said material back to the reducing means for further reduction.

In the drawings accompanying and forming a part of this application Figure 1 is a longitudinal sectional view of the classifier taken on the line 1—1 of Figure 6 looking in the direction of

the arrows and showing the parts in normal position.

Figure 2 is a view similar to Figure 1 and showing the filling of material to be classified into the container or body of the classifier and the separating or classifying of such material and settling of the coarse material in the body.

Figure 3 is a view similar to Figure 2 showing the container or body in lowered position and the closure actuated to discharge from the body material settled therein.

Figure 4 is a cross sectional view of the container or body taken substantially on the line 4—4 of Figure 1 looking in the direction of the arrows and showing the manner of mounting the nozzles in the wall of the body or container.

Figure 5 is a sectional view of the upper portion of the container or body taken substantially on the line 5—5 of Figure 7 looking in the direction of the arrows to show the mounting of a manually operative lever to actuate the closure for the lower end of the body.

Figure 6 is a side elevation showing the classifier in conjunction with material reducing means to receive and classify material delivered thereto from the reducing means and the returning of material settled in and discharged from the body of the classifier to the reducing means; and

Figure 7 is a plan view looking at the top of Figure 6.

In the embodiment of the classifier illustrated there is provided a container in the form of a tubular or cylindrical body or hopper 8 open at the opposite ends and preferably of truncated form and may be constructed of sheet metal, such as boiler plate. The body is yieldingly supported in inverted position to have vertical or upward and downward linear movement, and normally urged upwardly to predetermined position with no material or load in the body, by tie rods 9 having an eye 10 at one pivotally engaging eye or yoke members 11 fixed to the upper end of and spaced 90 degrees apart about the body. The rods 8 slidably engage in and extend through openings in beams or sills 12 supported upon a suitable foundation, or they may constitute the beams of a building, and coiled springs 13 engaged on the rods are seated on blocks 14 on the beams, the springs being confined between said blocks and abutments 15 threaded onto the rods. The springs normally urge the rods and thereby the connected body upwardly and are calibrated to retain the body in its upper position with no load in the body and permit of downward movement of the body proportional with the load or quantity of material therein, and the tension of the springs may be varied by screwing the abutments onto or outward on the rods 8.

The material to be classified is filled into the body through a tubular chute 16 which leads from the outlet of a bin and extends centrally into the top of the body 8, the material delivered from the chute being spread and directed oppositely to the side of the body by a deflector in the form of a plate 17 of greater cross sectional area than the chute and supported in opposed and spaced relation to the end of the chute by bolts 18 extended downward through openings 70 in a flange extended laterally from the end of the chute with the heads of the bolts engaging said flange and supported thereby, the bolts extending through openings in the plate 17 and the plate supported on the bolts by nuts threaded onto the bolts below the plate, the plate prefer-

ably being supported in inclined position as shown to permit of the ready flow of the material from the plate.

To retain material in and control the discharge thereof from the body there is provided a valve 5 or closure in the form of a conical head 20 supported exterior of the body with the conical surface opposed to and adapted to be seated against the end of the body, said end of the body being reinforced for this purpose by a circular 10 or annular plate 21 extending about and secured to the exterior of the body. The closure 20 is carried by a rod 22 extended upward axially through the body and supported and connected at the upper portion to the body to transmit 15 the upward and downward movements of the body to the rod and closure to effect closing movement of the closure by the upward movement of the body and closing the lower end of the body in the uppermost position of the body, 20 and effect opening movement of the valve or closure proportionately with the quantity of material in and downward movement of the body. For this purpose a sleeve 23 having diametrically oppositely extending pairs of ears is adjustably 25 mounted on the rod and supported in adjusted position between a pair of nuts 24 threaded onto the rod, one nut above and the other nut below the sleeve. Each one of a pair of links 24 is pivotally connected at one end between 30 a pair of ears of the sleeve 23 and the opposite end pivotally mounted on the blocks 14, and said links 24 connected with the body 8 by links or brackets 25 fixed at one end to and extending upward from bars 26 fixed to and extending 35 transversely of the top of the body, the upper end of the links 25 being pivotally connected to the links 24 near the end at which said latter links are mounted on the blocks 14, whereby to multiply the movement of the body transmitted 40 to the closure carrying rod 22.

The material filled into the body is classified by streams of liquid, such as water, entered into the body and subjecting the material filled into the body to the action of said streams of water 45 and the water in the body to separate particles of material from the mass of predetermined degree of fineness or specific gravity and flow the same off with the water from the top of the body, the coarse material settling in the lower 50 portion of the body. For this purpose nozzles 55 are mounted in the wall of and open into the body. As shown these nozzles are spaced in two rows about the body and the rows spaced longitudinally of the body and from the opposite ends thereof. To connect the nozzles with a source of liquid supply each of the nozzles is connected to a pipe 28 connected with an interposed valve 29 to one of a pair of branch pipes 30 disposed at opposite sides of the body between 60 the rows of nozzles and connected with a main supply pipe 31 leading from the source of supply and provided with a shut off valve 32. The nozzles are arranged so that the streams issuing therefrom are directed in an upwardly diverging 65 direction and tangential to the inner surface of the wall of the body, shown in Figure 4, whereby the initial material filled into the body, with the body in its upper position is subjected to the force of the streams and effecting a separation 70 of the material, and when the material consists of sand or colloidal matter and particles within a predetermined degree of fineness of specific gravity and cause the same to rise with the liquid in the body and flowed off with the flow of 75

the liquid from the top of the body and the coarser material settling in the lower portion of the body. When a predetermined quantity of material settles in the body it descends proportional with the weight of such material against the force of the springs and the closure 20 is moved to opening position proportional with the descending movement of the body effecting a discharge of the settled material, as shown in Figure 3. However, the actuation of the closure 20 is such that a quantity of material will have settled in the body before the closure is actuated to a level below the lower row of nozzles with the result that with the settling of the material there is also a dewatering of such material so that a minimum quantity of moisture or water is discharged with the material through the lower end of the body.

To direct the liquid overflowing from the body and the material flowed off therewith away from the body there is provided a launder in the form of a trough 34 carried by and disposed about the upper portion of the body 8 and consisting of an annular sheet metal member of substantially right angle form in cross section fixed to the wall of the body, as by welding or otherwise, with the vertically extending portion of said member extending in a plane above the top of the body and the horizontal portion or bottom declining from one side to the opposite side, as shown in Figures 5 and 6, with an opening in the side wall to cause the liquid to flow by gravity from the launder, the liquid discharged from the launder being directed away from the body by a chute 35, as shown in Figure 5.

To discharge all of the material from the body 8 manually operative means is provided to actuate the closure 20 to open position, comprising a lever in the form of a bar 36 pivotally mounted at one end at one side of the body on a bracket 37 fixed to and extending upward from the block 14 and the lever extending transversely and centrally of and beyond the opposite side of the body, as clearly shown in Figures 1 to 3, and connected to the closure carrying rod 22 to effect downward movement of the rod and thereby of the closure 20, as by a cable or chain 38. To connect the lever with the closure carrying rod 22 a portion intermediate the ends of the lever member is offset and adapted to engage at one side of the threaded end of the closure carrying rod. A strip 39 having an offset portion intermediate its ends, similar to the offset of the lever member, is fixed to the side of the lever member with the offset portion of the strip disposed at the side of the screw threaded end of the closure carrying rod opposite to and in opposed relation to the offset of the lever member and the lever connected with the closure carrying rod by nuts 40 threaded onto the rod below and above the offset portions of the lever member and strip and by means of which nuts the closure carrying rod 22 may be adjusted axially relative to the connection of the lever member with said rod.

In operation the body is filled with water when the material, such as ore, to be classified, or in the case of sand to be washed and classified is filled into the container and the admission of water into the body from the nozzles continued during the filling of the material into the body the streams of water issuing from the nozzles due to the arranging of the nozzles to discharge the water in upwardly diverging directions tangential of the wall of the container setting up a swirling action of the water and agitation of the material and effecting separation of material from the

mass within a predetermined degree of fineness or specific gravity. The quantity of material retained in the body before the closure 20 is actuated to discharge the material from the body is controlled by the adjustment of the closure 5 relative to the body effected by adjusting the nuts 40 on the closure carrying rod 22. The adjustment of the nuts 40 raises or lowers the level of the material filled into the body before it is discharged, such material being maintained at a 10 predetermined level that corresponds with a constant feed of material to the body. The maximum quantity of material that may be filled into the body before the material is discharged from the body is the filling of the material into 15 the body until it rises to a level slightly below the deflector plate 17. When shutting down the apparatus the material is subjected to the action of the water issuing from the nozzles and in the body without the filling of material into the body 20 until the overflow clears up when the flow of the water to the nozzles is shut off, as by the valve 32. The closure is then actuated by the lever 36 to discharge the material settled in the body and when the water on top of the material begins to 25 discharge the lever is released to permit of the closure 20 assuming its closing position.

In Figures 6 and 7 there is shown an adaptation of the invention for the reducing and classifying of material, such as ore, and means for returning the coarse material settled and discharged from the body of the classifier. The reducing means is shown in a conventional manner in the form of a gyratory crusher C supported at a higher elevation than the classifier. 30 The material to be reduced is fed to the crusher by a feeder, shown at F in a conventional manner as of the disk type to which the material is delivered from a bin B. A chute 16 is provided for the delivery of the material discharged from the crusher to the classifier. The classifier functions in the manner hereinbefore described and to return coarse material discharged from the classifier to the crusher for further reduction there is provided a conveyor, shown as of the 35 bucket type 40 passing around a pulley 41 rotatably supported above the crusher and a pulley 42 rotatably supported below the classifier, the conveyor travelling in a housing H. The material is delivered from the classifier to a receiver 43 having a hopper bottom with an outlet therefrom 40 adjacent to an opening in the conveyor housing 50 whereby to deliver material through said outlet to the conveyor buckets. The material is delivered from the conveyor buckets through an opening in the conveyor housing to a bin 44 and to the crusher from said bin through a chute 45 leading from the bottom of the bin to the crusher 55 inlet.

Having thus described my invention, I claim: 60

1. In material classifying means, a container having a hopper outlet supported to have vertical movement and into the top of which container solid material to be classified is filled, a closure to control the outlet, and nozzles adapted for connection with a source of liquid supply mounted on and opening through the wall to the interior of the container to direct the streams from the nozzles, said nozzles being disposed in axially spaced horizontal rows and arranged in upwardly diverging direction tangential to the wall of the container and set up a swirling action of the liquid in the container to effect a separation of particles of material of predetermined degree of fineness from the material as it is filled into the container and flow off the separated material 65

with the liquid from the top of the container and the remainder of the material settling in the container.

2. In material classifying means, a conical container having a hopper outlet supported in vertical position and open at the top through which to fill the material to be classified into the container, a closure for the outlet operative to control the discharge of material from the container, a launder disposed about the exterior and extending upwardly above the top of the container, and nozzles adapted for connection with a source of water mounted on and disposed in horizontal rows about the wall of the container one row adjacent the top and one row adjacent the lower end of the container, and said nozzles opening to the interior of and arranged to direct the streams therefrom into the container in upwardly diverging directions tangential to the wall 10 of the container and set up a swirling action of the water in the container to effect a separation of particles of material of predetermined degree of fineness from the material as it is filled into the container and flow off the separated material 20 with the water from the top of the container into and from the launder and permit the solid material to settle in the bottom of the container.

3. In material classifying means, a vertically supported inverted conical body open at the top and having an outlet in the bottom, a material feeding chute opening centrally to the top of the hopper arranged with means to direct the material in a stream laterally to the side of the hopper, a closure to control the outlet, nozzles disposed about and opening through the wall to the interior of the body adapted for connection with a source of and to deliver streams of water into said body in upwardly diverging directions tangential to the wall of the body and set up a swirling action of the water in the body and subject the stream of material delivered into the body to the action of the swirling water in the body to effect separation of particles therefrom and flow the same with the water from the top of the conical body, means operative by the quantity of material collected in the conical body to control the actuation of the closure and discharge of material from the body, a lever having a fixed pivot support connected to the closure 40 for the outlet of the hopper and manually operative to actuate the closure to outlet opening position.

4. In material classifying means, an inverted truncated conical container open at the top and having an outlet at the bottom, a closure to control the outlet, a chute arranged centrally in the top of and through which to deliver material into the container, a plate carried by the chute in spaced relation to the end thereof and inclining

at an angle to the horizontal to receive material from the chute and deflect it toward the side of the container, nozzles mounted on the container wall in axially spaced horizontal rows intermediate the top and bottom thereof and opening to the container, said nozzles being adapted for connection to a source of water and arranged to deliver streams of water into the container in upward diverging directions tangential to the wall of the container and set up a swirling action of the water in the container and subject the material filled into and deflected laterally toward the side of the container to the action of the swirling water to separate particles therefrom and flow the same with the water from the top of the container and the remainder of the material settling in the container, and the closure for the outlet being operative to close the container outlet to collect and effect dewatering of the settled material therein and to open the outlet to discharge material from the container outlet.

5. In material classifying means, a hopper means to support the hopper in vertical position to have upward and downward movement, a material inlet chute opening to the top of the container to fill material into the hopper, a deflector plate carried by and spaced from the outlet of the chute to have adjustment toward and away from the outlet of the chute and adapted to receive material delivered from the chute and direct such material laterally in a stream toward the side of the hopper, a closure to control the hopper outlet to retain material in the hopper and discharge of material from the hopper, springs to yieldingly support and urge the hopper upwardly to predetermined position and permit of downward movement of the hopper proportional with the quantity and weight of material therein, means to movably support the closure independent of the hopper, means to connect the closure supporting means to the hopper and operative by the upward movement of the hopper to actuate the closure supporting means to move the closure to outlet closing position and to outlet opening position by the downward movement of the hopper, and means to admit water into the hopper in upwardly diverging streams tangential to the wall of the hopper and set up a swirling action of the water in the hopper and subject the material delivered from the deflector plate into the hopper to the action of said swirling water to separate particles below a predetermined specific gravity from the material filled into the hopper and flow off the separated particles with the water from the top of the hopper.

JOSEPH E. KENNEDY.
